UNITED STATES PATENT OFFICE.

JOHN HEFFERON, OF CHEYENNE, WYOMING.

DRAFT-REGULATOR FOR FURNACES.

1,088,572.

Specification of Letters Patent.

Patented Feb. 24, 1914.

Application filed April 24, 1913. Serial No. 763,403.

To all whom it may concern:

Be it known that I, JOHN HEFFERON, a citizen of the United States, residing at Cheyenne, in the county of Laramie and State of Wyoming, have invented certain new and useful Improvements in Draft-Regulators for Furnaces, of which the following is a specification, reference being had therein to the accompanying drawing.

10 This invention relates to certain new and useful improvements in draft regulator attachments for furnaces and is particularly adapted to be used in connection with locomotives; the object being to provide a draft regulator in the form of a deflector plate which can be readily attached and used in connection with the ordinary door of the locomotive, whereby a direct draft will be prevented from striking the flue and crown-sheet of the furnace.

15 Another object of my invention is to provide means for adjustably mounting the deflector plate forming the regulator, whereby the size of the door opening can be regulated.

20 Another object of the invention is to provide a deflector plate which is so constructed that when in position, it will not interfere with the door in any way and one which can be thrown up out of operation.

Other and further objects and advantages of the invention will be hereinafter set forth and the novel features thereof defined by the appended claim.

25 In the drawings—Figure 1, is an elevation of a portion of a locomotive showing the application of my improved deflector plate forming the draft regulator, applied thereto; Fig. 2, is a vertical section through a portion of the furnace showing the position of the deflector plate within the door opening or frame; and Fig. 3, is a perspective of the deflector plate, detached.

Like numerals of reference refer to like parts in the several figures of the drawings.

In the drawings, 1 indicates the front of the furnace of a locomotive; 2 the door opening or frame over which is arranged a hinged fire door 4 of any suitable construction. Ar-

50 ranged over the door opening in vertical alignment therewith, is the ordinary oil cup 5; the above description being given so that the operation of my improved draft regulator when used in connection with the door opening of a furnace can be readily understood.

Fixed on the front 1 of the furnace over the door opening, are spaced angle irons 6, the lateral flanges 7 of which, are provided with inclined notches 8 forming keepers or 60 bearings for the supporting pin 9 of the deflector plate 10 which is preferably provided with an eye 11 in which the pin 9 is rigidly secured. The lower end of the deflector plate is offset as shown at 12 and is 65 slightly reduced as shown at 13 so as to extend into the door opening 2 when the door 4 is open, to deflect the air entering through the opening.

By adjusting the supporting pin 9 of the 70 deflector plate 10 in its supporting bearings vertically in either direction, the size of the opening 2 can be regulated in order to regulate the draft, and it will be seen that when the door is opened the deflector plate partly 75 closes the upper portion thereof in order to prevent a draft of cold air from passing directly to the flues and crown-sheet of the boiler.

It will also be seen that by providing a 80 deflector plate of this construction, a more perfect combustion is obtained in the fire box so as to form a partial smoke consumer and prevents any gases from escaping out of the door opening. It will also prevent the 85 boiler from throwing out black smoke or fire and protects the fireman from the direct heat radiating from the fire box through the door opening when the door is opened.

The deflector plate is so constructed that 9 when in use it fits snugly within the upper portion of the door opening, and is so mounted that it can be swung upwardly under the oil cup 5 out of the way when not in use.

From the foregoing description, it will be seen that I have provided a draft regulator which is especially adapted to be used in connection with locomotives, and comprises a deflector plate which can be adjusted vertically in respect to the door opening so as to regulate the draft; and at the same time prevents the cold air passing directly to the crown-sheet and flues, whereby a more perfect combustion is obtained within the fire box.

I claim:

The combination with a furnace, having a door opening and a door of a larger diameter than said opening for closing the same, of angle irons secured upon said furnace above said door opening provided with a series of inclined notches, a deflector plate

provided with an eye at its upper end having a pin arranged therein provided with projecting ends mounted within companion notches of said angle plates, said plate having a laterally extending reduced lower end capable of extending into said door opening when said door is in closed or open position.

In testimony whereof I affix my signature in presence of two witnesses.

JOHN HEFFERON.

Witnesses:
